UNITED STATES PATENT OFFICE.

ANDREW J. FAIR, OF WALNUT COVE, NORTH CAROLINA.

DESIGN FOR A MANTEL.

SPECIFICATION forming part of Design No. 26,853, dated March 30, 1897.

Application filed February 11, 1897. Serial No. 623,014. Term of patent 7 years.

To all whom it may concern:

Be it known that I, ANDREW J. FAIR, a citizen of the United States, residing at Walnut Cove, in the county of Stokes, State of North Carolina, have invented and produced a new and original Design for a Mantel, of which the following is a specification, reference being had therein to the accompanying drawings.

Figure 1 is a front elevation of a mantel, showing my design. Fig. 2 is a perspective view of the same on a smaller scale.

Like letters of reference indicate like parts in the different views.

The leading features of my design consist in the rectangular outlines along the upper portion of the mantel beneath the projecting ledge or shelf and the centrally-disposed rectangular outlines beneath the same, with rectangular outlines at the upper ends of the vertical supports or uprights. These rectangular outlines are those of drawers in the cross and vertical portions of the mantel.

A A are the vertical side pillars of the man-

tel. They are of parallel side portions with fanciful edges. B is the ledge projecting at the front and both sides of the mantel at the top. Beneath this projecting ledge or shelf is a series of rectangular drawers C, while beneath the same and disposed centrally of the mantel is the drawer D, of rectangular outline, as shown. At the upper ends of the pillars A are the drawers E, of rectangular outline.

All of the above-mentioned rectangular outlines are within the portion inclosed by the outer edges of the pillars and cross portion above the same.

What I claim is—

The design for a mantel, substantially as herein shown and described.

In testimony whereof I affix my signature in presence of two witnesses.

ANDREW J. FAIR.

Witnesses:

W. H. CRAIG,
A. B. LAMBERT.
